UNITED STATES PATENT OFFICE.

ZACHARY TAYLOR CREGO, OF COLUMBUS, OHIO.

DOOR-HANGER.

1,029,913.

Specification of Letters Patent. Patented June 18, 1912.

Application filed February 16, 1911. Serial No. 608,994.

To all whom it may concern:

Be it known that I, ZACHARY T. CREGO, a citizen of the United States, residing at Columbus, in the county of Franklin and State of Ohio, have invented certain new and useful Improvements in Door-Hangers, of which the following is a specification.

My invention pertains to an improved type of door hanger for sliding doors and it 10 is particularly designed to provide a door hanger wherein all of the several parts may be readily adjusted and arranged to compensate for wear and unnecessary looseness of operation.

15 It is further aimed to provide an operative structure in which the several parts may be readily dismantled to facilitate repair and adjustment by increased accessibility.

20 Particularly, the structure is devised in such a manner that the relative angles of the carrier head, the tracks and the sliding doors may be altered in practically any degree.

25 The preferred embodiment of my invention is shown in the accompanying drawings, in which—

Figure 1 is a side elevation showing one unitary portion of the structure, Fig. 2 is a 30 vertical section taken on line 2—2 of Fig. 1, Fig. 3 is a detail view of the particular type of adjusting mechanism utilized preferably at one end of the track structure, owing to the inaccessibility of this end, Fig. 4 is a detail view of the outer end unit, showing a 35 preferred form of spacing structure for the carrier rails, and, Fig. 5 is a detail view of the removable hanger for supporting the doors from the rollers.

40 Referring specifically to the several figures of the drawing, in which similar characters of reference designate corresponding parts, a header or support designated 1 is utilized as the track carrying member and, 45 as shown in the drawings, is provided with spaced bolt members 2 and 3 preferably extending through plates 4—5 and 6—7. These bolts 2 and 3 are vertically adjustable by means of nuts 8 and 9 and locked in adjusted position by means of lock nuts 10 and 50 11. At one end of the header 1, apertures

are provided for the reception of the legs of a staple 12 which is vertically regulable by means of nuts 13.

Carried by the heads of bolts 2 and 3 are substantially U-shaped hangers 14—15 having their lower ends bent laterally inward. At one end the staple 12 coöperates with a hook member 16. Carried by the inward extensions of the legs of the members 14—15 are spacing rods 17 and 18. Abutting these rods 17 and 18 on their outer surfaces are tracks 19 and 20 preferably of hard wood and clamped against the legs of the portions 14—15 by metal strips 21 and 22 bolted thereto. The ends 23 of the track members are spaced apart by a block 24 which may be of wood and which serves both as a spacing block and a connecting medium between the hook member 16 and the track structure. 70 The members 14 and 15 are preferably rigidly connected to the track structure, where-as the member 16 is connected for adjustment by means of nuts 25 and 26 threaded thereon and disposed respectively above and 75 below the spacing block.

The connecting medium between the track structure and the door 28 comprises hook members 29 adapted to hook upon the axles 30 of spaced rollers 31. A reduced extension is provided as at 32 upon the lower ends of the hook members 29 and this extension is preferably threaded and adapted to coöperate with internally threaded collars 33 having flanges 35 upon which rest apertured plates 34 for attachment to the door 28.

80 The operation of this structure will be apparent if it be considered that the device shown in the drawings, is practically one of two units which are used in coöperative relation in the form of two sliding doors and complementary door hanger mechanism. It is again emphasized that practically any degree of adjustment may be effected by means of the connecting devices between the header, 90 the tracks and the doors.

95 What I claim, is—

A door hanger comprising a track supporting element, spaced vertically adjustable pins, a staple adjustably supported at 100 one end of the track supporting element, a trackway, inverted U-shaped hanger straps

supporting said trackway at their lower ends and supported from said spaced vertically adjustable pins, a vertically adjustable hook carried upon the extreme inner end of
5 said track and adapted for detachable support from said staple, rollers operating on said trackway, a sliding door, hook members detachably grasping the axles of said rollers, and collars rotatably mounted on

said door and having a threaded adjustment 16 connection with said hook members.

In testimony whereof I affix my signature in presence of two witnesses.

ZACHARY TAYLOR CREGO.
